UNITED STATES PATENT OFFICE.

CARL G. PINGEL, OF BUTTE, MONTANA.

PIN-KEEPER.

SPECIFICATION forming part of Letters Patent No. 712,330, dated October 28, 1902.

Application filed January 2, 1902. Serial No. 88,135. (No model.)

To all whom it may concern:

Be it known that I, CARL G. PINGEL, a citizen of the United States, and a resident of Butte, in the county of Silverbow and State 5 of Montana, have invented a new and Improved Pin-Keeper, of which the following is a full, clear, and exact description.

This invention relates to improvements in keepers of pins of brooches and the like; and 10 the object is to provide a keeper of simple construction that will be closed or moved to a locked position by the insertion of a pin and having a guard to cover the pin-point, thus preventing any possibility of the point 15 scratching a person or becoming caught in a dress or the like.

I will describe a pin-keeper embodying my invention and then point out the novel features in the appended claim.

20 Reference is to be had to the accompanying drawings, forming a part of this specification, in which similar characters of reference indicate corresponding parts in all the figures.

Figure 1 is a perspective view of a pin- 25 keeper embodying my invention. Fig. 2 is a section on the line $\alpha\alpha$ of Fig. 1. Fig. 3 is a similar section, but showing the keeper open; and Fig. 4 is a section on the line $\gamma\gamma$ of Fig. 2.

30 Referring to the drawings, 1 designates a pin mounted to swing on a plate 2, which may represent a brooch or the like.

The keeper for the pin-point consists of a plate of metal bent to form a loop member 3 35 and the finger members 4, spaced from the loop member, the pin being designed to pass between the parts 3 and 4.

The locking device consists of a plate 5, pivoted between the members 4 and having a 40 hook member 6 at one end, which may be termed the "inner" end, and a hook member 7 at its opposite or outer end.

Attached to the hook member 7 and extending transversely thereof is a guard or hood 8 for the pin-point. This guard or hood 45 8 is longitudinally curved, and at its end toward the pivotal point of the pin 1 it is provided with a slight recess 9, in which the pin may engage.

In operation when the pin is moved inward 50 between the parts 3 and 4 it will first engage with the hook 6, so that by a continued inward pressure on the pin the locking device 5 will be moved to a closed position, as indicated in Fig. 2, with the pin-point underneath 55 the guard or hood and the outer end impinging on the pin-point, so as to prevent any possibility of the point engaging in clothing or scratching a person's fingers.

When it is desired to release the pin, pressure applied to the finger-piece 10 on the part 5 will move it to the open position, allowing the pin to swing outward.

Having thus fully described my invention, I claim as new and desire to secure by Letters 65 Patent—

A pin-keeper consisting of a plate bent to form a loop member and finger members spaced from the loop member, a locking-plate pivoted between the finger members and having hook ends, and a guard carried by the locking-plate, the said guard being longitudinally curved and provided at its inner end 70 with a recess to receive the pin, the outer end being adapted to engage on the point of 75 the pin, substantially as specified.

In testimony whereof I have signed my name to this specification in the presence of two subscribing witnesses.

CARL G. PINGEL.
